UNITED STATES PATENT OFFICE

115,538

DESIGN FOR A DIME BANK

John Boros, New York, N. Y.

Application March 28, 1939, Serial No. 83,871

Term of patent 7 years

To all whom it may concern:

Be it known that I, John Boros, a citizen of the United States, residing at New York, in the county and State of New York, have invented a new, original, and ornamental Design for a Dime Bank, of which the following is a specification, reference being had to the accompanying drawing, forming part thereof.

In the drawing, Fig. 1 is a side elevation of a dime bank, showing my new design; Fig. 2 is an edge view thereof, and Fig. 3 is a plan view.

I claim:

The ornamental design for a dime bank, as shown.

JOHN BOROS.
